UNITED STATES PATENT OFFICE.

ELEANOR PARKER CUSHMAN, OF DODGE, GEORGIA.

FASTENING DEVICE FOR SHOE-ORNAMENTS.

1,120,035.

Specification of Letters Patent.

Patented Dec. 8, 1914.

Application filed February 21, 1913. Serial No. 749,985.

To all whom it may concern:

Be it known that I, ELEANOR PARKER CUSHMAN, a citizen of the United States, residing at Dodge, in the county of Walker 5 and State of Georgia, have invented new and useful Improvements in Fastening Devices for Shoe-Ornaments, of which the following is a specification.

This invention relates to a fastening device for securing bows and like ornaments on shoes, particularly the fronts of ladies' shoes.

The object of the invention is to provide a simple, cheap and secure fastening means 15 of light weight to which a bow or similar ornament may be quickly attached by a few stitches of thread and as quickly removed by cutting or breaking the stitches when after use the ornament becomes soiled, mussed or 20 missshapen.

A further object is to provide the fastening means with a ready method of attaching it to a shoe so as to hold the bow or ornament in place thereon and when it is desired to make a change in the ornament the fastener may without trouble be easily removed from the shoe.

At the present time women's shoes are ornamented by securing to the front thereof 30 bows made of silk, ribbon, leather or other material either flat or gathered and attached to the shoe in various ways. It is a fact that on shoes so ornamented, the bows are the first thing to look shabby about the shoe, especially bows made of silk ribbon. The bows gather dust, become stained with shoe 35 polish when cleaning the shoe and mussed and made unshapely by rubbing and brushing. When the bows are in this condition it is desirable to remove them from the shoe and substitute new ones in place thereof, but so far as I am aware no simple and ready means has been devised whereby this 40 may be done.

With the present invention the bows may be quickly and easily attached to and removed from the fastening devices and the latter as readily secured to and removed 45 from the shoes.

The simplicity of the device enables the bows to be removed from the shoes when the latter are to be cleaned and put on again 50

when the shoes are to be worn and, furthermore, the construction of the device is such that it does not add materially to the weight 55 of the shoe and in fact increases but slightly the weight of the bow to which it is attached.

These objects and other advantages are secured by means hereinafter set forth in 60 the detailed description and illustrated in the accompanying drawing of which,

Figure 1 is a top view of the toe of the shoe with a flat ribbon bow applied thereto. Fig. 2 is a bottom plan view of a similar 65 bow and a fastening device secured thereto. Fig. 3 is a front view of the bow and the fastening device in position on the shoe showing one form by which the fastening device is connected to the shoe. Fig. 4 is a 70 perspective view of the fastening device disconnected from the bow. Fig. 5 is a view similar to Fig. 3, showing a different means for attaching the fastening device in place. Fig. 6 is a bottom plan view of a gathered 75 bow and the form of fastening device which I prefer to use with such bows.

In the drawing 10 designates a skeleton base plate made of thin resilient metal, preferably curved as shown in Fig. 3, one 80 end of which is bent up to form a catch 11 to engage the end of a tongue 12 formed by doubling the base plate upon itself as shown, the tongue preferably being made narrower than the base plate. The resiliency of the 85 metal from which the plate and tongue are made is such that the tongue may be sprung laterally with little or no effort to disengage its end from the catch 11 when it is desired to fasten and unfasten the same. 90 The plate 10 has a relatively narrow body portion and near each end of the body portion and on opposite edges thereto in the plane of the plate project lugs or fingers 13, through each of which small holes 14 are 95 bored for a purpose to be described later, this body portion with the outstanding lugs or fingers forming a light skeleton base plate or support.

Lying close against the back of the base 100 plate 10 is a sheet 15 of flexible material preferably woven wire and so shown. This sheet in the form shown in Figs. 2 to 5, inclusive, is fastened to the base plate by

strands of wire 16 extending through the holes 14 in the fingers 13 and through the mesh in the plate 15. This woven wire plate 15 forms a foundation upon which the flat 5 ribbon bow 17 is placed, the latter being secured to the plate by stitches 18, the thread passing through the mesh in the plate and into the bow.

It will be seen that with the plate 15 having 10 the numerous meshes or openings therein in a relatively large area is provided for the bow-holding stitches, and bows of different designs and shapes may be readily and securely attached, since the point of 15 stitching or attaching such bows may be conveniently shifted to any particular spot on the plate 15 where it is desirable to secure or stitch the bow. Furthermore, this plate 15 being of ductile material and projecting at its ends and sides beyond the skeleton base plate, as shown in Fig. 2, may be bent or shaped to suit the bows and permit the surface to which the bow is stitched to be given slightly different shapes and 20 contours in order to give different and proper "sets" to the different types of bows which may be attached thereto. As thus designed when a bow attached to the fastening device, as described, becomes soiled or 25 mussed, it is only necessary to cut or break the stitches 18 and the bow will be separated from the fastening device, the latter being then ready for the attachment of another bow. The plate 15 is preferably made a little 30 shorter and narrower than the bow so as to give a firm support to the bow and hold it securely in place. Where gathered bows are used I prefer the arrangement shown in Fig. 6, that is to say the reticulated plate 15 is omitted, the bow being 35 stitched directly to the fingers 13 of the skeleton plates through the holes 14 therein. Bows provided with fastening devices such as this are attached to the shoes by disconnecting the tongues 12 from the catches 11 40 and slipping the tongues through loops or eyes 19 secured to the shoes. These eyes or loops may be of thread, wire, leather or any other material, or if desired slits 20 (see 45 Fig. 5) may be made in the shoe and the tongue slipped thereinto as shown. In fact any suitable means capable of holding the tongue in place on the shoe may be employed.

55 What I claim is:

1. A fastening device for shoe bows and the like comprising a skeleton base-plate having a narrow body-portion; integral lugs or arms projecting at right angles from 60 said body portion near each end thereof, said arms having perforations to receive securing strands by which a superposed object may be secured to said base-plate; an integral catch at one end of said body portion, 65 an integral resilient tongue at the other end

of said body-portion to engage said catch, and bow supporting means secured to said plate.

2. A fastening device for shoe bows and the like comprising a skeleton base-plate 70 having a narrow body-portion and outstanding arms, a catch and catch-engaging tongue on said body-portion, and a bow-supporting plate of wire-gauze of larger area than said skeleton base-plate detachably secured to said base-plate. 75

3. A fastening device for shoe bows and the like comprising a skeleton base-plate of resilient material having a narrow body-portion and integral arms or lugs extending 80 therefrom, a catch at one end of said body portion, a catch-engaging tongue at the other end of said body-portion, and a reticulated bow supporting plate of ductile material and of larger area than said skeleton 85 base-plate detachably secured thereto.

4. A fastening device for shoe bows and the like comprising a curved skeleton base-plate having a narrow body-portion and integral outstanding lugs at the ends of said 90 body-portion and lying in the same plane therewith, an integral catch at one end of said body portion, an integral catch-engaging tongue extending from the other end of said body portion, and a bow-supporting 95 plate of ductile wire-gauze and of larger area than said skeleton base plate detachably secured to said arms by strands passing through the mesh and perforations in the arms of the base plate. 100

5. A fastening device for shoe bows and the like comprising a base plate formed with an integral catch at one end and an integral spring tongue at the other end adapted to engage with said catch, and 105 a plate detachably mounted on the base plate to which a bow or the like may be secured by stitching.

6. A fastening device for shoe bows and the like comprising a base plate formed 110 with an integral catch at one end and an integral spring tongue at the other end and adapted to engage with said catch, fingers projecting from the sides of the base plate through which are perforations, and a reticulated plate on one side of the base plate 115 and detachably connected thereto by strands passing through the perforated fingers and the openings in the reticulated plate, said reticulated plate serving as a base for a 120 bow or the like which may be attached thereto by stitching.

7. A fastening device for shoe bows and the like comprising a base plate made of thin resilient metal, an integral catch at one 125 end of the base plate, a tongue formed by bending the other end of the base plate upon itself, said tongue adapted to engage attaching means on a shoe and be retained by said catch, perforated fingers projecting 130

from the sides of the base plate, a plate of wire gauze on one side of said base plate, and strands passing through said perforated fingers and the mesh of the wire gauze plate 5 for attaching said gauze plate to the base plate, said wire gauze plate forming a foundation for a bow or the like which may be attached thereto by sewing.

In testimony whereof I have hereunto set my hand in presence of two subscribing 10 witnesses.

ELEANOR PARKER CUSHMAN.
